AUTOMATIC EXCESS HEAT PROTECTOR, ESPECIALLY FOR ELECTRIC MACHINES AND APPARATUS.

Application filed December 4, 1924, Serial No. 753,820, and in Germany December 31, 1923.

This invention relates to an automatic excess heat protector for the protection of machines and apparatus against overheating. The protector comprises a case within which there is arranged a cartridge for cut-outs formed by a guide with a slide movable therein in longitudinal direction, a spring pressing on the slide, a fuse arranged in a chamber and preventing the slide from moving longitudinally, the slide being arranged on a plunger, one end of the plunger being connected with said spring and the other end with the fuse. If the latter blows, a warning or safety signal is released. In a suitable construction of my improved protector an electric switch is actuated by the longitudinal movement of the plunger carrying the slide, which slide may be constructed to close or to open a circuit. This switch may be arranged on the inside or on the outside of the case enclosing the guide and the slide. Suitably the slide may be formed as a current bridge arranged at a right angle with the direction of the guide, so that the contact making parts are arranged outside of the range of both guides. If by the movement of the slide a circuit is to be closed by this movement the contact making parts get in contact with two current-carrying poles, if however by the movement of the slide a closed circuit is to be opened, by this movement the contact making parts are removed from the current-carrying poles, the poles being arranged on the inner wall of the case and connected with two terminals on the outside of the case. Suitably the chamber enclosing the fuse may be formed separate of the room within the case, for instance by a capped nut screwed on the lower end of the case, so that the fuse when blowing cannot be injurious to the guide and the slide.

Some constructions according to my invention are illustrated in the accompanying drawings by way of example.

45 Figs. 1 and 2 each are a vertical section illustrating one form of device constructed in accordance with the present invention.

Fig. 3 is a cross-section on line A—A of Fig. 1.

50 Fig. 4 is a view from below of Fig. 1.

Referring to the drawing a shell 1 of insulating material such as fibre is provided with two lateral projections 2. A connect-

ing terminal 3 is secured within each projection 2 and covered by an insulating protecting cover 4 threaded on the terminal 3. The terminals 3 are provided with contact surfaces 5 situated within the shell 1 and making contact with two bolts 6. The bolts 6 are movably mounted within a tube 7 and pressed by a small helical spring toward the contact surfaces 5 in order to insure good contact with them. Each of the bolts 6 is guided in a longitudinal slot 10 of the tube 7 by means of a small pin 9. A plunger 12 of insulating material is arranged within a socket 13 mounted in the shell 1, the tube 7 being secured within a transverse bore of a guide portion or slide 11 formed on the plunger 12. The guide portion 11 projects through a wide transverse slot 14 of the socket 13 into a guide slot 15 formed in the inner wall of the shell 1. The socket 13 is provided with a flange 16 adapted to be seated on the end of the shell 1. At the upper end of the plunger 12 there is secured a head 17 by means of a screw. A helical spring 18 is supported by a disc 19 mounted on the flange 16 and presses against the head 17, the disc forming a guide for the upper part of the plunger 12. The disc 19 and the socket 13 are pressed on the shell 1 by means of a capped nut 20. A pin 21 having a head 22 is secured to the lower end of the plunger 12. 23 designates a disc-shaped fuse, the melting-point of which is predetermined according to the permissible heating temperature of the apparatus or machine equipped with the automatic excess heat protector. In order to be mounted on the pin 21 the fuse is provided with a recess 24. The lower end 25 of the socket 13 is threaded, a cap 26 made of a suitable material of a high heat conductivity, such as metal, being screwed thereon. The cap 26 is formed with a central recess 27 for receiving the head 22. When assembled, the cap 26 presses the fuse 23 toward the lower front-wall of the socket 13.

The described construction of the excess heat protector is designed for electromotors, 100 transformers and other highly loaded apparatus, as well as for generators. The shell 1 is screwed in a corresponding bore of the shell of the machine or apparatus to be protected from excess heat. A conductor 105 of the apparatus or the machine is connected

to the terminal 3. The cap 26 surrounding the fuse 23 is to be arranged near that portion of the machine or apparatus which is most exposed to the danger of excess heat, or it may be mounted immediately on that portion, in order to quickly impart the temperature of superheating to the fuse, thereby causing the interruption of the electric current in due time, as will be described below. The cap 26 is fitted with a covering 28 of any heat insulating material, in order to prevent it from being cooled, especially on ventilated motors or other ventilated machines or apparatus. The interruption of the current is obtained in the following manner: At a certain temperature of excess heat the fuse 23 blows and allows the spring pressed plunger 12 to move upward to the position shown in Fig. 2, the bolts 6 leaving the contact surfaces 5. The plunger 12 of insulating material enters between the contacts 5, thereby preventing the formation of an arc. In order to repair the switch, the caps 20 and 26 are removed and the socket 13 together with the plunger 12 are withdrawn from the shell 1. After removing the remnants of the fuse, the head 17 is pressed downward until the pin 21 projects from the opening of the socket 13. Thereon a new fuse is mounted on said pin, the socket 13 with the plug is inserted again in the shell 1 and the caps 20 and 26 replaced.

The excess heat protector could also be multipolar. In this case the plunger 12 would be fitted with a corresponding number of conducting bridges 6, 7. The excess heat protector could also be formed in such manner that the current is closed by it instead of being interrupted. In this case, at the position of the plunger 12 as shown in Fig. 1, the conducting bridge formed by the bolts 6 and the tube 7 would be displaced with regard to the contact surfaces 5. The bolts 6 would be mounted on the spring pressed plunger 12 below the contacts 5 and would move between them only when the fuses have blown, thereby causing for instance an electromagnetic switch in the circuit to operate.

50 We claim:

1. A device of the character described, comprising a tubular casing adapted for attachment to a machine to be protected

against excessive heat, a pair of electrical terminals disposed at diametrically opposite points in said casing, an insulating sleeve supported within the casing with one end thereof extending outside of said casing, an insulating plunger slidable within said sleeve, a cap threaded on said casing for retaining said sleeve therein, said cap being perforated to permit the passage of the plunger therethrough, a pair of contact members carried by said plunger normally in contact with and closing a circuit through said terminals, a fusible member engaging said plunger and the extended end of the sleeve thereby to retain the plunger in circuit-closing position, resilient means in engagement with said plunger and adapted to move the same out of circuit-closing position upon removal of said fusible member, and a cap removably secured to said sleeve and enclosing said fusible member.

2. A device of the character described, comprising a tubular casing adapted for attachment to a machine to be protected against excessive heat, a pair of electrical terminals disposed at diametrically opposite points in said casing, an insulating sleeve supported within the casing with one end thereof extending outside of said casing, an insulating plunger slidable within said sleeve, a cap threaded on said casing for retaining said sleeve therein, said cap being perforated to permit the passage of the plunger therethrough, a pair of contact members carried by said plunger normally in contact with and closing a circuit through said terminals, a pin secured in said plunger and having an enlarged head, a fusible disk having a radial slot therein adapted to straddle said pin and engage said head, said disk being adapted also to engage the extended end of the sleeve thereby to retain the plunger in circuit-closing position, resilient means in engagement with said plunger and adapted to move the same out of circuit-closing position upon removal of said fusible disk, and a cap removably secured to said sleeve and enclosing said fusible disk.

In testimony that we claim the foregoing as our invention we have signed our names.

WILHELM HICKEL.
OTTO PLETSCHER, JUN.
